DETONATOR

Helmut Junghans, Schramberg-Sulgen, Germany

Application December 4, 1936, Serial No. 114,251
In Germany January 18, 1935

8 Claims. (Cl. 102—39)

This invention relates to detonators of the kind which are furnished with centrifugal jaws for securing the firing pin, and has for its object to provide a construction in which the centrifugal jaws are not released for movement until expiry of a certain period of time after the projectile has been fired.

Detonators having centrifugal jaws have already been proposed, in which the said jaws are released by the reaction immediately the projectile is fired, so that they commence to move outwards as soon as the centrifugal force starts to take effect.

According to the invention, the actuation of the jaws, which in turn release the firing pin, is deferred by the fact that a retarding means is included between the element releasing the jaws (for example a reaction member) and the jaws themselves.

The retarding device comprises a portion which is operated by centrifugal force and a second portion which is connected with the first portion and projects into the path of the centrifugal jaws, this second portion blocking the centrifugal jaws over a certain part of the movement of the operating portion and thereupon releasing the same. The blocking portion is connected with the centrifugal portion by means of teeth. If the centrifugal jaws, in the manner known per se, are so arranged that the one jaw can only swing out when the preceding jaw has reached its extreme swung-out position, merely the first centrifugal jaw is caused to be acted upon by the retarding device.

In accordance with the invention there are also provided means for slowing down the operation of the retarding device, together with a suitable safety means for transport.

The invention is illustrated in a possible form of embodiment in the accompanying drawing.

Fig. 1 shows a detonator in longitudinal section with the parts in the locked position.

Fig. 2 is a view of the detonator parts, with the cap removed in the direction A in Fig. 1.

Fig. 3 is a plan view of the detonator parts, with the cap removed, in the position according to Fig. 1.

Fig. 4 is a plan view of the retarding device, partly in section, in the position according to Fig. 1.

Fig. 5 is a longitudinal section through the detonator with the parts in the released position.

Fig. 6 is a plan view of the detonator parts according to Fig. 5 with the cap removed.

Fig. 7 is a plan view of the retarding device

similar to Fig. 4. The retarding device is in the position in which the first centrifugal jaw is released.

Fig. 8 shows the centrifugal jaws in the swung-out position.

In the axis of the detonator casing *a*, *b* there is located the firing pin *c* furnished with a collar *d*, below which there engage the front ends of the centrifugal jaws *e1*, *e2*, *e3*, *e4* when these are in their normal position. The centrifugal jaws *e* are mounted to swing about pins *f*. A centrifugal member or operating segment *g* is arranged eccentrically and carries a toothed segment *h* which engages with a corresponding pinion *i*. With the pinion *i* there is firmly connected a locking element in the form of a bell or an annular casing *k*, which is engaged by abutments or pins *l* on the centrifugal jaws *e*, so that the centrifugal jaws are held together towards the center and are unable to swing out. In the periphery of the annular casing *k* there are provided evenly spaced slots *m*, in such fashion that after a certain rotary movement on the part of the ring the pins on the jaws are situated in front of the slots and are able to enter the same, whereby the centrifugal jaws swing outwards.

If the centrifugal jaws, as shown in the drawing, are arranged in such fashion that one centrifugal jaw swinging out as first jaw alone does not release the adjacent jaw until it has reached its extreme position, and this second jaw in turn releases the next jaw, and so forth, it is merely necessary for the purpose of securing the centrifugal jaws to furnish only one of these, viz., the first jaw, with an abutment which engages below the retarding ring, as in this way all other jaws are also secured. Corresponding with the one pin there is then provided merely one slot for the passage of the same in the periphery of the ring.

For securing the operating segment *g* during the transport of the detonator there is provided on the segment a projection *g1* bearing against a spring *n* which projects into the path of movement of the segment and the free end of which carries a weight *n1*. The projection and the end of the spring bear against each other with bevelled faces. Below the free end of the spring there is provided a recess into which the spring is able to enter.

In accordance with an additional feature of the invention there is also provided, for the purpose of delaying the release of the firing pin to an even greater extent than provided for by mere rotation of the safety ring and the ar-

angement of the centrifugal jaws, a locking or braking element *o*, which is pressed by the centrifugal force against the locking ring *k*. This braking element is constructed in the form of a two-armed lever, the shorter arm of which is furnished with a projection adapted to engage with correspondingly formed teeth *k1* provided on the periphery of the retarding ring *k*, whilst the other arm possesses a comparatively greater length and thickness for the purpose of being able to act as centrifugal member. In certain circumstances the projection on the shorter arm may be made resilient. Naturally the braking element *o* will have a considerably smaller mass than the operating segment *g* functioning on the same casing, so that the rotation of the casing will not be braked to a standstill.

The operation of the detonator is as follows:—

Upon the firing of the projectile the safety spring *n* will be forced under the action of the inertia out of the path of the operating segment *g*, and following thereon will be held in the depressed position by the projection *g1* of the operating segment, which commences to move upon the initiation of the centrifugal force. In this way the operating segment is free to move. During the swinging out of this segment there is rotated at the same time owing to the engagement of the teeth the pinion *i*, which in turn causes rotation of the annular element *k* connected therewith, which element forms the safety means for the centrifugal jaws *e*. This ring is rotated until its incision reaches the safety pin *l* of the centrifugal jaw *e1*. The same, under the action of the centrifugal force, now passes with its jaws through the slot towards the outside. It is not until the centrifugal jaw *e1* has reached its outer position that the jaw *e2* and then *e3* and finally *e4* are able to follow, the firing pin *c* then being free for percussive firing. During the rotation of the safety ring *k* the braking element *c* engages with its projection in the corresponding teeth of the ring and thus additionally retards its operation.

Having now particularly described and ascertained the nature of my said invention, and in what manner the same is to be performed, I declare that what I claim is:

1. In a detonator for a projectile, a firing pin, centrifugal jaws for securing the firing pin and adapted to swing out successively for the purpose of releasing the pin, an abutment on the first of the said jaws, and a rotatable locking portion disposed centrally in the detonator and furnished with a slot through which the said abutment is adapted to pass for the purpose of release.

2. In a detonator for a projectile, a firing pin, centrifugal jaws for securing the firing pin, an annular rotatable casing mounted centrally in the detonator on the said pin, a centrifugal member for communicating motion to the retarding means, teeth on the said casing, and a toothed segment on the said centrifugal member engaging with the teeth of the said casing.

3. In a detonator for a projectile, a firing pin, centrifugal jaws for securing the firing pin, a rotatable locking portion for the said jaws disposed centrally in the detonator, teeth on the said locking portion, and a two-armed lever having a projection on the shorter arm, the heavier arm of the said lever pressing the said projection under the action of centrifugal force into the said teeth. 5

4. In a detonator for a projectile, a firing pin, 10 centrifugal jaws for securing the firing pin, a rotatable locking portion for the said jaws disposed centrally in the detonator, a centrifugal member for retaining the said locking portion in the locked position in the condition of rest, a 15 spring projecting into path of movement of the said centrifugal member, and a weight on the free end of the said spring, the said spring being adapted to be swung out of the path of movement of the centrifugal member by the force of 20 reaction occurring upon the firing of the missile for the purpose of releasing the parts.

5. A detonator for projectiles, comprising a firing pin with means for operating it by impact on the target, centrifugal jaws capable of holding the firing pin in safety condition, a locking element rotatable in the detonator, said element normally retaining the jaws in such holding position, and means actuated on firing the projectile to cause said element to rotate, said element 30 having means for releasing the jaws after it has made a certain rotation during which the projectile has travelled a determined distance from the muzzle of the gun from which it was fired, the firing pin thereupon being freed for operation 35 by its impact means.

6. A detonator according to claim 5, in which the means actuated on firing the projectile includes a centrifugally movable segment geared to the rotatable element. 40

7. A detonator for a projectile, comprising a firing pin operable by impact on the target, centrifugal jaws securing the firing pin against impact operation when the jaws are closed and releasing it for such operation when the jaws are 45 open, wheel gearing acting to retard the opening of the jaws during a determined initial portion of the flight of the projectile, and a centrifugally actuated brake operative on the wheel gearing to assist its retarding action. 50

8. A detonator for a projectile, comprising a firing pin operable by impact on the target, centrifugal jaws securing the firing pin against impact operation when the jaws are closed and releasing it for such operation when the jaws are 55 open, wheel gearing acting to retard the opening of the jaws during a determined initial portion of the flight of the projectile, and a lever with two unequal arms pivoted in the detonator and having a projection on its shorter arm, the greater arm of the said lever pressing the projection under the action of centrifugal force against the wheel gearing to assist its retarding action. 60
